UNITED STATES PATENT OFFICE.

WALTER E. BANNING, OF SYRACUSE, NEW YORK.

DESIGN FOR A HANDLE AND BASE FOR RUBBER STAMPS.

SPECIFICATION forming part of Design No. 21,091, dated October 6, 1891.

Application filed July 14, 1891. Serial No. 399,522. Term of patent 3½ years.

To all whom it may concern:

Be it known that I, WALTER E. BANNING, a citizen of the United States, residing at Syracuse, in the county of Onondaga and State 5 of New York, have invented and produced a new and original Design for a Base and Handle for a Rubber Stamp; and I do hereby declare the following to be a full, clear, and exact description of the same, reference being had to 10 the accompanying drawing, forming a part thereof.

My invention consists of a new design for a base and handle for a rubber stamp; and its object is to give such an article an ornamental 15 appearance and configuration, and whereby it may be readily distinguished from other bases and handles for rubber stamps that may be in the market.

My new and original design is clearly illustrated in the accompanying drawing, which 20 is an isometric view of said base and handle for rubber stamps.

Referring to the drawing, A is the base, of 25 rectangular form, comprising, essentially, a right-lined figure or object of four sides and a horizontal top and bottom surface, the opposite and equal sides $a a'$ being equal and parallel and also vertical, and the equal opposite sides $b b'$ being practically parallel and 30 oblique or beveled, the direction of inclination of the said sides or faces $b b'$ being toward each other upwardly, as is clearly delineated, said base portion A thus being of substantially parallelogrammic contour or conformation.

35 B is a narrowed or contracted handle rising perpendicularly and centrally from the upper surface of the base A, said handle portion

at its parallel perpendicular sides $c c'$ extending parallel with the perpendicular sides $a a'$ 40 of the parallelogrammic base A and the length thereof, while its narrow sides (or edges) $d d'$ are oblique and lineal with the oblique sides $b b'$ of the base portion, and consequently converging toward each other upwardly, and the 45 top e of the said handle is horizontal.

The leading features of my design consist in the practically rectangular base and the handle perpendicular on two opposite sides, oblique upwardly and inwardly on its other 50 two opposite sides (or edges) said obliquity lineally continuing down and incorporating the adjacent and contacting sides of the rectangular-shaped parallelogrammic base, and said handle truncated upwardly. 55

What I claim is—

The design for a base and handle for a rubber stamp herein shown and described, comprising the rectangular and parallelogrammic base, the handle rising centrally therefrom, 60 having two opposite sides perpendicular and the remaining two opposite sides or edges oblique, said obliquity continuing lineally down and including the adjacent parallel sides of the base portion, and said continuously-oblique base and handle sides lineally converging upwardly and terminating in a truncated handle-top. 65

In testimony whereof I affix my signature, in presence of two witnesses, this 16th day of January, 1891.

WALTER E. BANNING. [L. S.]

Witnesses:

WM. C. RAYMOND,
M. E. CRUMB.
